US00D596076S

(12) **United States Design Patent**
Kelley et al.

(10) **Patent No.:** **US D596,076 S**
(45) **Date of Patent:** **** Jul. 14, 2009**

(54) **OFF-HIGHWAY TRUCK**

(75) Inventors: **Craig B. Kelley**, Dunlap, IL (US); **Gary C. Bryant**, Chillicothe, IL (US); **John J. Maas**, Mount Zion, IL (US); **Michael J. Vance**, Sahuarita, AZ (US); **Andrew M. Rummer**, Forsyth, IL (US); **Larry T. Ryterski**, Peoria, IL (US); **Kolin J. Kirschenmann**, East Peoria, IL (US); **Robert W. Briggs**, Lexington, KY (US); **Don J. Robinson**, Decatur, IL (US); **Clifford E. Miller**, Marseilles, IL (US); **Terry A. Coins**, Decatur, IL (US); **Matthew P. Jacobs**, Fuquay-Varina, NC (US)

(73) Assignee: **Caterpillar Inc.**, Peoria, IL (US)

(**) Term: **14 Years**

(21) Appl. No.: **29/285,500**

(22) Filed: **Mar. 30, 2007**

(51) **LOC (9) Cl.** **08-10**

(52) **U.S. Cl.** **D12/15**

(58) **Field of Classification Search** D12/1, D12/5, 22, 15, 93, 98, 196, 14; D15/10, D15/25, 30, 33; 414/245, 685, 688, 722, 414/724, 493; 108/234, 641; 37/403, 413, 37/442, 443, 412; D21/558, 559, 562, 561

(57) **CLAIM**

The ornamental design for an off-highway truck, as shown and described.

DESCRIPTION

FIG. 1 is a front perspective view of our new design.

FIG. 2 is a rear perspective view thereof;

FIG. 3 is a right view thereof;

FIG. 4 is a left view thereof;

FIG. 5 is a top view thereof;

FIG. 6 is a left, front perspective view thereof; and,

FIG. 7 is a right, front perspective view thereof.

The bottom view does not form part of the claimed design and therefore is not disclosed.

The elements depicted in dashed lines form no part of the claimed design.
